UNITED STATES PATENT OFFICE.

JONATHAN DAVIS, OF PHÆNIXVILLE, PENNSYLVANIA.

MACHINE FOR THREADING TAPE INTO EDGINGS.

SPECIFICATION forming part of Letters Patent No. 708,130, dated September 2, 1902.

Application filed April 24, 1902. Serial No. 104,484. (No model.)

To all whom it may concern:

Be it known that I, JONATHAN DAVIS, a citizen of the United States, residing at Phœnixville, in the county of Chester and State of Pennsylvania, have invented certain new and useful Improvements in Machines for Threading Tape into Edgings, of which the following is a specification.

My invention has relation to that class of machines adapted to insert tape in lace edgings, and in such connection it relates to a novel form of a star-wheel which is adapted as the edging is advanced to automatically shift each alternate bar of the edging upon a needle to interlace the same with the bars of the edging and to provide a grooved bar to receive the tape.

The principal objects of my invention are, first, to provide in a machine for inserting tape in lace or edgings a star-wheel the star-like projections of which engage each alternate bar of the lace or edging to raise and deliver the bar upon a needle and to permit passing of a succeeding bar under the needle to interlace the body of the needle into the lace or edging as the same is advanced upon the needle; second, to actuate the star-wheel by each alternate bar of the lace or edging to permit the proper insertion of the needle under and over the bars independent of the varying or unequal distance of the bars from each other, and, third, to provide in such a machine a grooved tape-bar adapted to receive and hold the tape and to be readily engaged and clamped as well as disengaged from the needle.

The nature and scope of my invention will be more fully understood from the following description, taken in connection with the accompanying drawings, forming part hereof, in which—

Figure 1 is a longitudinal sectional view of a machine embodying main features of my invention. Fig. 2 is a top or plan view of said machine, the upper portion thereof being removed. Fig. 3 is a side elevational view, enlarged and partially sectioned, of the star-wheel for engaging alternate bars of the lace or edging, a needle for receiving the bars, guides over which the lace or edging is adapted to be fed, a tension-arm for depressing the bars of the lace or edging, and ten-

sion-rollers for the lace or edging. Fig. 4 is a top or plan view of Fig. 3. Fig. 5 is an enlarged detail view illustrating a portion of 55 the needle and tape-bar and the tape inserted into the bar; and Fig. 6 is a side elevational view of Fig. 5, partially sectioned, illustrating the mode of uniting the tape-bar with the needle-body and clamping the end of the tape 60 between the said bar and body.

Referring to the drawings, in the machine as illustrated the lace or edging *a* is unwound from a reel *a'* and passes under a guide *a²* and flattening and friction rollers *a³* and *a⁴* 65 to stretch the lace or edging laterally and to maintain its bars *a⁵* in a flat or straight condition before presenting the same to a table *b*. To the under face of the table *b* is secured a guide *b'*, which is adapted to engage the 70 bars *a⁵* of the edging and to guide the same to two upwardly-projecting and curved guide-fingers *b²* and *b³*, between which a star-wheel *C* is adapted to rotate. The table *b* is furthermore provided with a spring-arm *b⁴*, the curved end *b⁵* of which is centrally located between the guide-fingers *b²* and *b³* and which is adapted to depress the 75 tape *a* between said bars *a⁵* of the fingers for a purpose to be presently more fully explained. The star-wheel *C* is loosely mounted on a shaft *c'*, secured to a standard *c²* and held in frictional contact with the same by a spring *c³*, mounted on the shaft *c*, as illustrated in Figs. 3 and 4. The star-like projections *c⁴* of the star-wheel rotate between the curved guide-fingers *b²* and *b³* and between which the curved delivery end *d'* of the threading-needle *D* is located, so as to permit the free rotation of said wheel and its projections. 80 The threading-needle *D* is held in a horizontal position by milled feed-rollers *e*, *e'*, *e²*, *e³*, *e⁴*, and *e⁵*, which also engage the edging *a* and in their rotation feed the edging forward from left to right of the machine. In order to insure the proper and alternate presentation of the bars *a⁵* of the edging *a* to the star-wheel *C*, the bars *a⁵* in the forward travel of the lace or edging beneath the table *b* are first depressed by the guide *b'*. In this depressed 85 condition the bars *a⁵* are then presented to the upwardly-projecting guide-fingers *b²* and *b³* and then beneath the tension-arm *b⁴*, which depress the bars between the fingers, as well 90 95 100

as between the star projections c^4 of the star-wheel C, which projections, however, are only permitted to engage the bars a^5 after the same have traveled over the forward portion of the 5 guide-fingers b^2 and b^3 , as illustrated in Fig. 3. The free ends of the guide-fingers are depressed, permitting the star projections to project above the fingers in such manner that a forward sliding bar will first engage the 10 straight portion c^5 of the notched end of the projection c^4 until it is prevented from further movement thereon by abutting against the finger c^6 of the notched end. The bar a^5 in its forward movement will now rotate the 15 star-wheel C until the projection c^4 has delivered the bar a^5 of the edging a upon the downwardly-projecting end d' of the needle D and until the fingers c^6 of the projections c^4 are disengaged from the bar a^5 by the bar a^5 sliding forward on the needle D, at which time 20 the star-wheel C comes to a standstill. The next succeeding bar a^5 of the edging, however, will not be engaged by a star projection c^4 of the star-wheel C, since the distance of the 25 projections c^4 from each other is greater than the distance of the bars a^5 of the edging a from each other. The succeeding bar a^5 , following the bar raised by the star projection c^4 , will slide forward over the fingers b^2 and 30 b^3 , and the end b^5 of the tension-arm b^4 by depressing the bar a^5 will conduct the same under the end d' of the needle D and in this manner interlace the needle D into the 35 lace or edging. The star-wheel being rotated by the bar a^5 of the lace or edging a , which has been deposited upon the needle D, brings another of the star projections c^4 in such a 40 position that a bar a^5 , following the bar fed under the needle D, will engage the projection c^4 and rotate the wheel C, as hereinbefore described. In other words, each alternate bar a^5 of the edging a will be engaged 45 by a star projection c^4 of the star-wheel C and placed upon the needle D. The rotation of the star-wheel C by alternate bars of the lace or edging avoids the necessity of having the bars a^5 arranged a predetermined distance apart from each other, since the proper operation of the star-wheel is made entirely in 50 dependent of location and distance of the bars a^5 from each other. It therefore follows that the proper interlacing of the threading-needle D into the edging will in all instances be accomplished whether the bars a^5 of the edging follow each other in regular or irregular sequence. The lace or edging delivered upon the needle D is fed over the body of the same by the milled rollers e^1 , e^2 and e^3 , and 55 e^4 and e^5 and onto a grooved bar E, adapted 60 to receive the tape f to be inserted into the edging. In order to connect the grooved bar E with the needle D, the same is provided with a contracted extension d^2 of such shape that when the extension is inserted into the 65 grooved bar the sides and upper and under face of the needle-body will be in alinement with the grooved bar E, as illustrated in Figs.

5 and 6. The end of the tape f is at the same time securely clamped between the extension d^2 of the needle D and the grooved bar E by 70 placing the tape around the edge of the grooved bar, which slides under the extension d^2 and between the same and a leaf-spring d^3 , preferably integral with the needle D. The leaf-spring d^3 furthermore holds the grooved 75 bar E in engagement with the extension d^2 of the needle D and at the same time affords means of ready connection and disconnection of the needle to and from the grooved bar E. The groove e in the bar E is of sufficient 80 depth to prevent the contacting of the bars a^5 of the lace or edging a with the tape f during the feeding of the bars a^5 over the grooved bar E. To maintain the body of the needle D and the grooved bar E firmly in position 85 in the machine during interlacing of the needle into the edging and during feeding of the same over the needle and the grooved bar, the first two sets of milled feed-rollers e^1 , e^2 and e^3 are grooved to receive the contracted body 90 of the needle D, whereas the last set of milled rollers e^4 and e^5 is channeled to accommodate the flat grooved bar E. The tension exerted upon the lace or edging a by the tension-rollers a^3 and a^4 and the milled rollers e^1 , e^2 , e^3 , and e^4 and e^5 is sufficient to hold the edging 95 a with the required amount of friction down upon the curved guide-fingers b^2 and b^3 and to maintain the same also in a flat condition. After all the lace or edging has thus been 100 placed upon the grooved bar E the needle is withdrawn from the bar and the edging removed from the bar, during which manipulation the tape f is properly inserted in the edging in the usual and well-known manner. 105

Having thus described the nature and objects of my invention, what I claim as new, and desire to secure by Letters Patent, is—

1. In a machine for threading tape into lace or edging, a wheel having radial projections, the peripheral face of said projections having a straight portion terminating in a finger, all arranged so that the distance between successive bars of the lace or edging to be fed is less than the distance between successive projections on said wheel. 115

2. In a machine of the character described, in combination with means for feeding the edging, a star-wheel, the projections of which having a straight face terminating in a finger, 120 said straight face adapted to engage and to permit a movement of alternate bars of said lace or edging and to be rotated by said bars by abutting against said fingers. 125

3. In a machine of the character described, 130 in combination with means for feeding the edging, a star-wheel having projections and straight faces terminating in a finger, the straight faces of said projections and the intervening spaces between the same adapted to receive and to permit a certain forward movement of the bars of said lace or edging. 135

4. In a machine of the character described, in combination with means for feeding the lace

or edging, a star-wheel, the projections of which have straight faces and a finger, said faces adapted to engage alternate bars of said edging and to be rotated by said bars by abutting against said fingers with a step-like movement and to permit the entrance of the bars intermediate of said alternate bars in the intervening spaces of said projections, said spaces being of greater width than the width of a projection so as to afford a free movement of said intermediate bars independently and during and after the step-by-step movement of said star-wheel, and a needle located between said projections adapted to receive the alternate bars above and the intermediate bars below the point thereof.

5. In a machine of the character described, in combination with means for feeding the lace or edging, a star-wheel, the projections of which have straight faces and a finger arranged at one end of said straight face, the faces being adapted to receive alternate bars of said lace or edging, and to be rotated by said bars by abutting against each finger successively by a step-like movement, and the intervening spaces of said projection being of greater width than the width of each projection and adapted to receive intermediate bars of the alternate bars to permit an independent forward movement of said intermediate bars in said intervening spaces of said projections, a needle arranged between said projections, curved guides adapted to present the alternate bars of said lace or edging to one pair of the projections of said star-wheel to feed the alternate bars of said lace or edging upon the needle, and a tension-arm adapted to feed the intermediate bars of said lace or edging passing over said curved guides below said needle so as to interlace said bars with said needles.

6. In a machine of the character described, in combination with a needle adapted to receive the lace or edging and mechanism for feeding the lace or edging toward the needle, a star-wheel having projections and straight peripheral faces terminating in successive fingers integral with said projections, and intervening spaces between said projections of a width greater than the width of each projection, the flat faces of said projections and intervening spaces between the same adapted to receive and to present bars of the lace or edging alternately above and below the point of the needle, and said star-wheel so arranged

as to be driven by alternate bars of said lace or edging by abutting against the fingers of said projections.

7. In a machine of the character described, in combination with a needle adapted to receive the lace or edging and mechanism for feeding the lace or edging over the needle and to maintain the same in a flat condition and taut position during said feeding, a star-wheel adapted to present the lace or edging to the needle so that the bars of the lace or edging are alternately above and below the point of the needle, said star-wheel arranged to be driven by the feeding of the lace or edging with a step-like movement, and means adapted to depress the bars of the lace or edging before and during presentation of the lace or edging to said star-wheel.

8. The combination, in a machine for inserting tape into lace or edging, of a flat grooved bar adapted to receive the tape, a needle and a star-wheel for feeding the lace or edging over the needle and the grooved bar and tape, said needle having a contracted and flat end for the reception of the grooved bar, and a spring adapted to clamp said bar to the contracted and flat end of said needle.

9. In a machine for threading tape into lace or edging, a star-wheel having a series of projections, each projection having a flat face terminating at one end in a finger, curved guides arranged adjacent to said star-wheel, said star-wheel and guides arranged in the path of the lace or edging in its passage through the machine, and means arranged between said guides and the projections of said star-wheel to depress the bars of said lace or edging as the same passes through the machine.

10. In a machine of the character described, a star-wheel having a series of radial projections separated from each other by a series of spaces wider than said projections, each projection having a flat face terminating at one end in a radial projecting finger, said spaces, flat faces and fingers mutually cooperating in the feeding of the lace or edging of the machine.

In testimony whereof I have hereunto set my signature in the presence of two subscribing witnesses.
